(57) **CLAIM**

The ornamental design for a squirrel baffle, as shown and described.

DESCRIPTION

FIG. 1 is a top perspective view of a squirrel baffle showing my new design;

FIG. 2 is a bottom perspective view thereof;

FIG. 3 is another bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 4;

FIG. 12 is an enlarged view of portion 12 in FIG. 8; and,

FIG. 13 is an enlarged view of portion 13 in FIG. 9.

The evenly dashed broken lines illustrate features of the squirrel baffle that form no part of the claimed design. The unevenly dashed broken lines define the boundary of enlarged views and form no part of the claimed design.
